UNITED STATES PATENT OFFICE.

LIVINGSTON L. LEAVELL, OF CLEVELAND, OHIO, ASSIGNOR TO ORR ENGINEERING CORPORATION OF NEW YORK, N. Y., A CORPORATION OF NEW YORK.

FUEL-OIL BURNER.

Application filed March 19, 1925. Serial No. 16,637.

To all whom it may concern:

Be it known that I, LIVINGSTON L. LEAVELL, a citizen of the United States, and a resident of Cleveland, county of Cuyahoga, and State of Ohio, have invented a new and useful Improvement in Fuel-Oil Burners, of which the following is a specification, the principle of the invention being herein explained and the best mode in which 10 I have contemplated applying that principle, so as to distinguish it from other inventions.

This invention, as has been indicated, relates to an improved fuel oil burner. More 15 particularly it comprises a burner particularly adapted for atomizing and vaporizing the liquid fuel preliminary to combustion.

In oil burners, as in many instances here- 20 tofore constructed, atomized fuel particles are projected from nozzles, or when vaporization upon a heated surface is made use of, no atomizing effect is produced, and said devices do not operate at maximum effi- 25 ciency.

The principal object of the present invention is to improve the construction of fuel oil burners. A further object is to provide a burner which will be simple to construct, 30 effective in operation and one which is not subject to rapid deterioration under conditions of severe service. Another object of the invention is to provide a fuel oil burner which will be automatic in its operation and 35 will direct the draft ascending through a central orifice over a heated inclined surface over which liquid fuel is sprayed, becoming atomized and vaporized preliminary to complete combustion. Another object of the in- 40 vention is to provide a safety marginal zone about the circumference of the burner to absorb excess liquid fuel at times when the burner is shut off and also to prevent the sudden snapping out of the flame. Other 45 objects will appear in the course of the following description. To the accomplishment of the foregoing and related ends, said invention, then, consists of the means herein- 50 after fully described and particularly pointed out in the claims.

The annexed drawing and the following description set forth in detail certain structure embodying the invention, such dis-

closed means constituting, however, but one of various structural forms in which the 55 principle of the invention may be used.

In said annexed drawing:—

Fig. 1 is a top plan view of one form of the improved burner, and Fig. 2 is a vertical central view partially in section of the 60 burner taken along the line 2—2 shown in Fig. 1.

As is clearly shown in the drawing the burner comprises a shell 1 having a substantially flat circumferential portion and a 65 frusto-conical central portion 2 surrounding a central opening 3 through which the draft for the burner is to be supplied. A cover or baffle plate 4 of dome-like shape is centrally supported, in a manner hereinafter 70 to be described, with its marginal portions 5 slightly overhanging and in spaced relation to the upper edge of the inclined portion of said burner. Said cover is preferably supported, as shown in Fig. 2, in adjustable relation to the upper edge of said burner by means of an adjusting screw 6 having its squared head 7 engaged within a recess 8 formed in the under side of said cover, and having its screw-threaded shank 75 engaged within a screw-threaded opening formed in the upper side of a distributing unit 9 in the fuel supply line. The fuel supply line 11 is brought in from a point below the burner and extends upwardly 80 centrally of the draft opening and through an aperture in a supporting bar 10 extending across the upper portion of the frusto- 85 conical member 2 to the distributing unit which is supported on said bar. A plurality 90 of branches 12 having downwardly turned nozzles 13 at their outer ends are connected with said distributing unit. Upon the upper side of each nozzle an air vent or nipple 14 is provided to assist in atomizing the fluid 95 issuing from said nozzle.

It will be noted that the frusto-conical portion of the burner is offset inwardly from the flat circumferential portion being connected thereto by means of a series of 100 circular steps 15, 16. An annular shell 17, having an inwardly projecting flange 18 at its upper edge, and a conical body portion corresponding to the frusto-conical central section of the burner, is adapted to have its 105 lower edge seated upon the lowermost of said

5 circular steps, with the inner edge of said flange positioned somewhat below the upper edge of the frusto-conical portion of the burner and in spaced relation to the adjacent wall.

10 The space between the shell and the inclined portion of the burner thus provides a hollow chamber 19 which is preferably filled with asbestos, or some similar insulating packing. The purpose of this insulation is to prevent the central air draft through the burner from having a cooling effect upon the outer wall of the shell. The outer wall 15 of the annular shell thus provides a "hot wall" for the burner against which the liquid fuel may be vaporized prior to its combustion.

20 The inwardly projecting flange of the annular shell is provided with a shallow groove upon its upper side into which the liquid emerging from the nozzles is received. The liquid fuel thus supplied becomes atomized when it strikes the grooved edge of the shell and mixes with the air currents immediately 25 adjacent the upper outer edge of the burner structure.

20 After the burner has been started by suitable means, such as a torch or a taper, the hot wall will become incandescent and the 30 liquid fuel will be vaporized through contact therewith. The flat circumferential portion of the burner is preferably provided with two concentric rows 21, 22, of upstanding ribs, in staggered relation to each other, and 35 an unbroken upstanding flange 23, spaced from the outer row of ribs. A packing of asbestos, or some other suitable material may be placed over the flat portion of the burner body between the inner row of ribs 21 and 40 said marginal flange 23. This packing will serve to absorb any excess quantity of fuel oil escaping down the inclined side walls of the burner and will assist in allowing the flame to gradually diminish when the fuel 45 supply is shut off and will eliminate the explosion which ordinarily takes place as the flame goes out. Outwardly of the marginal flange 23 just described a circumferential gutter or groove 24 is provided to receive 50 any excess fuel escaping from the nozzles and forming part of a safety device which is brought into operation when the flame of the burner is extinguished prior to the liquid fuel supply being cut off. In such event the 55 excess liquid fuel will flow into said outer groove and thence will pass into an overflow pipe 25 shown at one side of said structure which communicates with a safety cut-off mechanism of conventional form, which 60 automatically turns a valve in the fuel supply line.

65 The operation of the burner will be obvious from the description, but it should be pointed out that the redistribution of the draft from a point above the burner in a

70 downward direction adjacent the point of discharge of the liquid fuel supply through the several nozzles results in a combined atomizing and vaporizing action which is of great effectiveness in completely consuming the fuel supply and producing a high degree of heat. The provision of a separate shell adjacent the upper edge of the burner with insulating material between the same and the body of the burner insures the outer wall 75 being constantly maintained at a sufficient degree of temperature to satisfactorily vaporize the liquid fuel particles brought into contact therewith.

80 Adequate safety provision is supplied through the arrangement of a flash base circumferentially of the burner, said base having a shallow channel 31 within which insulating packing (not shown) may be provided, as well as the outer groove or channelway 32 for receiving an overflow of liquid fuel at a time when the flame of the burner is extinguished.

85 The burner as described is adapted to operate with either natural draft or forced draft. When small domestic installations are to be made the natural draft supplied to the furnace in which the burner is placed may provide adequate combustion and high 90 efficiency of operation. Forced draft may be used, however, where accurate control of the temperature is desired or where a large variation in the demands upon the heating apparatus is to be provided for.

95 In industrial installations it will usually be found desirable to employ forced draft supplied at a point below the central opening 3 of the burner shell. Such draft may be from a source of any preferred type, and a fan or a steam jet may be used as desired.

100 Other modes of applying the principle of my invention may be employed instead of the one explained, change being made as regards the structure herein disclosed, provided the means stated by any of the following claims or the equivalent of such stated means be employed.

105 I therefore particularly point out and distinctly claim as my invention:—

110 1. A liquid fuel burner comprising a base having an inclined central portion surrounding a central orifice, an annular shell having an inwardly directed flange at its upper edge positioned in spaced relation about said inclined portion of the body, and means for discharging liquid fuel against the upper portion of said shell to atomize and vaporize the same.

115 2. A liquid fuel burner comprising a base having an inclined central portion surrounding a central orifice, an annular shell having an inwardly directed flange at its upper edge positioned in spaced relation about said inclined portion of the body, and means for discharging liquid fuel against 120

125 130

the upper portion of said shell to atomize and vaporize the same, and means for diverting air emerging through said central orifice downwardly against the outer face of 5 said shell.

3. A liquid fuel burner comprising a base having an inclined central portion surrounding a central orifice, an annular shell having an inwardly directed flange at its upper 10 edge positioned in spaced relation to said inclined portion of the body, a shallow groove formed in the upper face of said flange, and means for discharging liquid fuel into said shallow groove and against the upper 15 portion of said shell to atomize and vaporize the same.

4. A liquid fuel burner comprising a base having an inclined central portion surrounding a central orifice, an annular shell having an inwardly directed flange at its upper 20 edge positioned in spaced relation to said inclined portion of the body, a shallow groove formed in the upper face of said flange, means for discharging liquid fuel 25 into said shallow groove and against the upper portion of said shell to atomize and vaporize the same, a central adjustable support and a dome resting freely upon said support above said central orifice having its 30 marginal edges depending in spaced relation to the upper portion of said annular shell for diverting air ascending through said central orifice downwardly about the outer surface of said shell.

5. A liquid fuel burner comprising a base having a flat outer portion and an inclined annular shell positioned centrally thereof, a grooved upper edge provided about said shell, a baffle disposed in spaced relation to 40 the upper edge of said shell, a series of nozzles for liquid fuel disposed adjacent the upper edge of said shell and adapted to discharge said liquid fuel into the grooved upper edge of said shell and against the inclined upper portion thereof, and a draft 45

conduit spaced from said shell to avoid a cooling effect of the draft thereon.

6. A liquid fuel burner comprising a base having a flat outer portion and an inclined annular shell positioned centrally thereof, 50 a grooved upper edge provided about said shell, a baffle positioned in spaced relation to the upper edge of said shell, a series of nozzles for liquid fuel disposed adjacent the upper edge of said shell, a draft conduit spaced inwardly of said shell to provide a hollow chamber adjacent the upper edge of the inclined portion of said shell, and a packing of insulating material within said hollow chamber to avoid a cooling effect of 55 the draft thereon.

7. A liquid fuel burner comprising a base having a flat outer portion and an inclined annular shell positioned centrally thereof, 60 a baffle positioned in spaced relation to the upper edge of said shell, a series of nozzles for liquid fuel disposed adjacent the upper edge of said shell, a draft conduit spaced from said shell to avoid all cooling effect 65 of the draft thereon, a shallow channelway surrounding the base portion of said burner, and a packing of insulating material within said channelway.

8. A liquid fuel burner comprising a base having a flat outer portion and an inclined 70 annular shell positioned centrally thereof, a baffle positioned in spaced relation to the upper edge of said shell, a series of nozzles for liquid fuel disposed adjacent the upper edge of said shell, a draft conduit spaced 75 from said shell to avoid all cooling effect of the draft thereon, a shallow channelway surrounding the base portion of said burner, a packing of insulating material within such channelway, a circumferential groove, and 80 an outlet connected with said circumferential groove.

Signed by me, this 18th day of March, 1925.

LIVINGSTON L. LEAVELL.
